UNITED STATES PATENT OFFICE.

GEORGE HAYES, OF NEW YORK, N. Y.

METALLIC LATHING.

SPECIFICATION forming part of Letters Patent No. 416,165, dated December 3, 1889.

Application filed October 1, 1888, Serial No. 286,901. (No model.) Patented in England October 23, 1888, No. 15,235; in France October 26, 1888, No. 193,756; in Belgium October 26, 1888, No. 83,740; in Italy October 26, 1888, No. 24,317, and in Canada January 23, 1889, No. 30,611.

To all whom it may concern:

Be it known that I, GEORGE HAYES, a citizen of the United States, and a resident of the city, county, and State of New York, have 5 invented a new and useful Metallic Lathing, (for which I have obtained patents in the following foreign countries: Great Britain, October 23, 1888, No. 15,235; France, October 26, 1888, No. 193,756; Belgium, October 26, 1888, No. 83,740; Italy, October 26, 1888, No. 24,317, and Canada January 23, 1889, No. 30,611,) of which the following is a specification.

My invention consists of a sheet or piece of 15 sheet metal having at near intervals throughout its extent oblong apertures of peculiar formation, each opening having been formed by making an incision through the sheet metal in clean-cut line and (without removing any portion of the metal during the operation) forcing outwardly to four sides, or two sides and two ends, the edge metal and giving the raised metal a curved shape or backward bend with its convexity toward the 20 opening, the curve continuing backward to sufficient extent to constitute the projecting metal, a hook or barb under and behind which the plaster may find lodgment and become clinched, thereby held to the surface of the 25 sheet.

It further consists of a sheet or piece of sheet metal provided with the aforesaid oblong apertures located at near intervals throughout, each opening having its four 30 sides (or two sides and two ends) cut to the desired shape and curved or bent outwardly and backwardly as tongues or lips, their convex surfaces facing each other, with the opening between, their convexity commencing at 35 the back plane of the sheet and as brought forward outwardly the curve of such nature as to bring the tongues toward each other, with their nearest points at about half their heights or projection, whereby is produced 40 between them and from their nearest points toward the back plane of the sheet a dovetail mold or cavity, widest at the back, into and through which the plaster will set and 45 form itself into a perfect dovetail key, locking 50 itself to the sheet by means of the open-

ings, each aperture being formed in the same manner.

It also consists of a combination of two of said clean-cut and backwardly-bent tongues or hooks triangularly shaped and adjacently located—one being forced outwardly and backwardly from one opening and the other forced similarly from another opening—their concave faces opposite each other, their arrangement with regard to each other and 55 proximity being such that the two serve in unison to constitute the space between them a dovetail mold or socket into which the plaster will set, forming itself into a perfect dovetail key, becoming locked to the surface 60 of the sheet.

In the accompanying drawings, Figure 1 represents a face view of a piece of the sheet metal with a portion of the same covered with plaster. The apertures are shown at intervals 70 with the edge metal turned outwardly. Where the same are covered by plaster, they are shown by dotted lines. At the upper left-hand corner the aperture is not shown as opened, but the lines representing the slits or 75 incision—a straight line with two branching lines at each end of the straight line as terminals. Fig. 2 is a sectional view lengthwise of the same sheet on the line *w x*.

In the drawings, A indicates the sheet or 80 piece of lathing, which may be of any desired dimensions.

B indicates the apertures through the sheet. They are of oblong shape and each have four 85 regularly-formed clean-cut tongues or lips. In forming said openings a straight cut or slit is made, as at *a*, with two branching or diverging cuts or slits at each end of the straight cut, as at *b*, and the triangularly-shaped edge metal thus produced being forced outwardly 90 and bent backwardly constitutes the four projecting tongues or lips. The operation is performed by a suitably-shaped die, which does the cutting and also turns outwardly and backwardly the edge metal with clean-cut 95 edges until it assumes the form shown.

C indicates the side tongues, and D the end tongues.

Between the convex faces of the projecting tongues, from their nearest points to their 100

base-line, is a space wider at back than front, forming, essentially, a dovetail mold, into which the plaster sets as a dovetail key.

E indicates plaster at the front of the lathing, and F that which has passed through the apertures B, and expanded at the back of the lathing forming knobs or hooks, also securing the plaster to the lathing. All of the tongues become hooks, around, behind, and beneath which the plaster sets, affording additional means whereby the same is effectually secured to the lathing. It may also be seen by reference to the sectional view, Fig. 2, that between the concave faces of two of said tongues or hooks C, one from one opening and the other from the adjacent opening, is another dovetail mold or socket (its back being the face of the sheet) into which the plaster is forced and set, shaping itself into another dovetail key securing the same to the sheet. Thus the plaster over the entire sheet is hooked and keyed at every point. The four tongues or projecting lips of the oblong openings are clean cut to their shape and with uniformity throughout the sheet, and not raised as burrs, (irregularly torn asunder with ragged edges,) but of a regular outline, so that plaster may fit and pack readily thereto.

The sheets may be cut and bent to suit any desired location, and used to form columns, pilasters, arches, niches, groins, &c.; also, they may be applied externally to walls, especially to frame buildings, and thereby both outside and inside rendered fire-proof.

35 What I claim as new, and desire to secure by Letters Patent of the United States, is—

1. A lathing of sheet metal, having rectangular or four-sided openings at intervals throughout, each opening having at its verge 40 a curved tongue of the metal, clean cut, projected from the sheet in forming the opening, the side edges of the tongue converging toward its free end in straight lines, and the tongue standing outwardly from the plane of the sheet with its convex face toward the opening, essentially as shown and described.

2. Sheet-metal lathing having at intervals throughout tongued apertures of oblong rectangular shape, the edge metal of each opening constituting the four sides thereof, not removed from the sheet, but curved outwardly and standing from the face of the sheet at each of the four sides of the opening as a projecting tongue or lip, the convex faces of the 55 tongues being oppositely arranged in such manner that a dovetailed mold is produced

into which the plaster will "set" as a dovetail key, essentially as shown and described.

3. The metallic sheet-lath described with oblong openings formed by cutting through 60 the sheet in a straight clean-cut line, as at a, also cutting through the sheet in the direction of the branching or diverging lines b at each end of the line a, and bending outwardly from the plane of the sheet the edge metal 65 with a curve to constitute the four projecting tongues or lips, as and for the purpose herein set forth.

4. A lathing of sheet metal, having at intervals throughout apertures formed by cutting 70 an incision, as a straight line, with two branching or V-shaped lines at each end of the straight line as terminals thereof, the incision clean cut, without jaggedness, and then bending outwardly and backwardly the edge metal 75 to constitute four raised and projecting tongues, two triangular and two truncated, essentially as shown and described.

5. A lathing of sheet metal, having at intervals throughout four-sided apertures, each 80 aperture having at its verge, standing outward from the plane of the sheet, four clean-cut and positively-shaped tongues or lips, two being pointed and two truncated, or having one straight edge parallel to the plane of the 85 sheet, essentially as shown and described.

6. Sheet-metal lathing provided with four-sided or oblong apertures at intervals throughout, arranged in diagonal lines across the sheet, each aperture having at its verge the four 90 clean-cut projecting tongues, as herein set forth, bent backwardly from the opening and shaped essentially as shown and described.

7. In a sheet-metal lathing, the combination of four projecting clean-cut tongues, each 95 having been turned outwardly from the sheet in forming the openings, shaped and arranged diagonally, as herein set forth, the arrangement of the tongues with regard to each other being such that a dovetail mold is produced with one of the tongues at each of four sides, the free ends of the tongues approaching each other with their concave surfaces facing, so that plaster inserted between will set as a dovetail key with the surface of the 105 sheet at its back, essentially as shown and described.

GEO. HAYES.
